CANDLE LIGHT

Roy L. Darling, Jersey City, N. J., assignor to
 Bond Electric Corporation, Jersey City, N. J., a
 corporation of Delaware

Application November 23, 1931, Serial No. 577,733

7 Claims. (Cl. 240—10.64)

This invention relates to battery containing electric candle lights or torch lights of the kind in which, when the candle light is stood upon a table or other supporting surface, the circuit through the lamp and battery is open and the lamp is not illuminated, while the circuit is completed automatically and the lamp is illuminated when the candle light is lifted off the supporting surface.

One object of the present invention is the provision of correlated features for simplifying the construction, increasing the efficiency and cheapening the cost of manufacture of such candle lights over those heretofore known, as well as rendering the same more convenient and simple to operate.

Another object of the invention is to provide a candle light so arranged that it may selectively be set to give a continuous light or become illuminated only when raised off its support, automatically extinguishing itself when its base is rested upon a supporting surface.

Still another object of the invention is the provision of a candle light circuit controlling mechanism, the inherent principle of which adapts itself to both conductive and non-conductive battery containers.

In accordance with the invention, a tubular casing contains the battery, one terminal of which is in constant electrical contact with one terminal of a lamp while the other battery terminal is in constant electrical contact with the movable contact of a circuit closure. The movable contact tends, normally, to be in circuit making engagement with a fixed contact in constant electrical connection with the other lamp terminal. In its normal circuit closing position the movable contact is disposed, at least in part, outwardly of the lower marginal surface of the base of the candle light so that when the base rests upon a supporting surface the movable contact is held away from the fixed contact and the circuit is interrupted. Provision is also made for permanently completing the circuit by movement or displacement of the circuit closing structure.

These and other objects of the invention and the means for their attainment will be more apparent from the following detailed description, taken in connection with the accompanying drawings illustrating various embodiments by which the invention may be realized, and in which:

Figure 1 is a view, in vertical section, showing a candle light, in accordance with this invention, resting upon a support whereby the circuit

through the battery and lamp is interrupted and the lamp extinguished.

Figure 2 is a fragmentary view showing the circuit controlling mechanism in closed circuit position.

Figure 3 is a view similar to Figure 2, but showing the displacement of the circuit closing structure to cause the candle light to be permanently illuminated.

Figure 4 is a bottom view of the circuit controlling mechanism taken on the line 4—4 of Figure 1 and looking in the direction of the arrows.

Figure 5 is a transverse sectional view taken on the line 5—5 of Figure 1 and looking in the direction of the arrows.

Figure 6 is a view similar to Figure 1, but showing a modification of the candle light structure.

Referring now in detail to the several figures of drawings and first advertiring to Figures 1 through 5, there is shown a metallic and preferably cylindrical battery casing 10 having its upper end 12 tapered and reduced in diameter to simulate the usual form of the upper end of a candle the extremity of the part 12 being turned 80 over in a transverse plane to form a flange 14 defining, conveniently, a circular hole receiving a lamp socket 16 for the base 18 of a lamp 20. Near its lower end, the casing 10 is pressed outwardly to form a bead 22 and at its lower extremity 85 it is threaded, as at 24, for the reception of a cap-like, or at least a generally cup-shaped, member 26 embodying the circuit closing element. The bottom of the cap 26 is formed with an opening 38 which may be said to be defined by the inwardly directed bottom flange 39.

In the illustrated embodiment, the battery is shown as formed of two individual cells 28 and the central or carbon terminal of the battery is adapted to be maintained in constant contact 95 with the central terminal of the lamp base 18 by means of a battery positioning element, preferably resilient, in the form of a coil spring 32 which is carried by the cup-shaped closure 26 and is conveniently utilized to cooperate and in a 100 sense function as a part of the circuit closing structure.

The coil spring 32 is out of contact with the walls of the container 10 and/or threaded end 24 thereof and is mounted, by means, say, of the 105 eyelet 36, upon a disc of insulatory or nonconductive material 34 resting on the flange 39. The disc 34 is, preferably, of a diameter to fit fairly snugly within the bottom of the cup-shaped cap 26 and closes thereby the opening 38, which is 110

- preferably circular and formed therein. In other words, the wall of the cup-shaped cap 26 is turned inwardly as a flange 39, which flange 39 defines the opening 38 in the bottom of the cap. Conveniently, the battery positioning element 32 rests upon a disc, preferably of wear resistant material 40, such as metal, which is carried by the insulatory disc 34 and is of a diameter less than the diameter of the disc so that when held in place by the rivet 36, it is held out of contact with the walls of the cap 26, although as will hereinafter more fully appear, it is of a diameter sufficient to contact with and bridge or close the open bottom end of the casing 10, as seen in Figure 3, and permanently complete the circuit through the lamp. At one portion of its perimeter, the disc 34 is formed with a notch 42 and a movable contact member moves within this notch from an open circuit position out of contact with the casing 10 or any part in electrical connection therewith to a closed circuit position in contact with the flange 39 which, of course, is in electrical connection with the casing 10. As illustrated, the contact member is formed by a transversely extending finger 44 mounted upon the extremity of a longitudinally extending arm 46 carried upon a ring of conductive material 48, which is secured to the disc of insulatory material 34 and in electrical connection with the battery positioning element 32 by which the circuit between the contact 44 and the negative terminal of the battery 28 is completed. As shown, the ring 48 is provided with a radially extending supporting part 50 which, at the center of the ring 48, is secured by the rivet 36. The conducting ring 48 is formed of resilient material and is so bent as to normally stand away from the disc 34, as shown in Figure 2, whereby the contact 44 tends to be in engagement with the flange 39 on the casing. When the ring 48 is pressed upwardly, as viewed in the drawings, the contact 44 is moved away from the flange 39 and the circuit is broken.
- The circuit of this candle light is traced as follows:
- From the central terminal 30 of the battery the current flows to the central terminal of the lamp base 18 through the filament of the lamp to the peripheral terminal of the lamp base 18, thence to the socket 16, and from the socket 16 through the metallic casing 10 to the threaded lower end 24. The conductive cap 26 is in electrical connection with the threaded lower end 24 and hence the circuit is completed through the cup-shaped closure, the flange 39 thereof, the contact 44, arm 46 and ring 48, eyelet 36 and battery positioning element 32 to the other terminal of the battery.
- Obviously, the casing 10 need not be of conductive material but may be of non-conductive material, for instance, fiber, in which event the circuit may be completed by any metallic strip extending between the socket 16 and the threaded end 24 for engagement either by the cap 26 or the metallic disc 40.
- The bead 22 on the casing 10 is utilized to fix the position of a base for the candle so as to give the effect of a candle stick, for instance. This base may take any convenient form and, as indicated, it is of relatively large diameter, as at 50, having a central upwardly extending tubular part 52 telescoping over the casing 10 below the bead 22, which positions the casing 10 with respect to the base. The two parts may, of course, be permanently secured together, as by welding or the like. The bead 22 also fixes the position of the

bottom cap, in one sense, with respect to a supporting surface T upon which the base 50 rests. That is, the flange 39 may be slightly above the supporting surface or in contact therewith when the base stands on the supporting surface, but must in no instance be sufficiently above the supporting surface to permit the movable contact 44-48 to move downwardly sufficiently to bring the contact 44 in engagement with the flange 39.

The parts in open circuit position are indicated in Figure 1. When, however, the candle light is lifted off the supporting surface T, the inherent resiliency of the ring 48 is sufficient to cause the same to move downwardly, as shown in Figure 2, to bring the contact 44 in engagement with the contact 39 to close the circuit, as has been described.

In some instances, it may be desired that the candle light give a permanent light although resting on a table. As shown in Figure 3, this is accomplished by screwing the cap 26 further on to the threaded end 24, thus bringing the disc 40 upwardly into contact with the end of the flashlight casing. Thus the disc 40 short circuits the contact and causes the illumination of the lamp. The circuit then is from the battery positioning element 32 to the disc 40 and from the disc 40 to the casing 10. When the circuit is to be interrupted, it is merely necessary to unscrew the bottom cap again sufficiently to move the disc 40 away from the end of the casing.

A modification of the invention is illustrated in Figure 6. At its upper end, the candle light does not differ materially from that construction shown in Figure 1 except that in the interest of a finished appearance, the flange 14 is cupped, as shown at 58, so that the clamping flanges of the socket 16 are hidden from view. At the lower end of the candle light, the connection between the two is simplified materially in the interest of manufacture. No bead 22 is formed on the casing 10. Instead, the upper end of the cap 26 is formed with an outwardly extending flange 60 and the base 62 is formed about the central hole which receives the casing 10 with spaced inwardly directed flange portions or a groove 64 receiving the flange 60. The cap 26 and base 62 can thus be readily clamped and secured together and the base 62 is affixed to the casing 10 merely by screwing on the cap 26.

Various modifications will occur to those skilled in the art in the composition, configuration and disposition of the component elements going to make up the invention as a whole, and no limitation is intended by the phraseology of the foregoing description or illustrations in the accompanying drawings, except as indicated in the appended claims.

What is claimed is:—

1. A candle light comprising, in combination, a casing having an opening in the lower end, a base for the casing, a flange surrounding the opening, a fibre disc carried on the flange inwardly thereof and formed with a passage, a battery engaging member, a conducting member of resilient material supported beneath the disc and having a bent portion normally disposed by virtue of the resiliency of said member below the base and a contact portion passing through the passage and overlying the flange, and means electrically connecting the battery engaging member with the conducting member.

2. A candle light comprising, in combination, a casing having an opening in the lower end, a base for the casing, a flange surrounding the opening,

5 a fibre disc carried on the flange inwardly thereof and having a notch in its periphery, a battery terminal engaging element, a conducting member of resilient material beneath the disc and having a contact portion within the notch and overlying the flange and conducting means securing the battery terminal engaging element and the resilient conducting member to the disc.

10 3. A candle light comprising, in combination, a casing having an opening in the lower end, a base for the casing, a flange surrounding the opening, a fibre disc carried on the flange inwardly thereof and having a notch in its periphery, a metallic disc carried above the fibre disc and spaced from the casing, a battery positioning spring, an eyelet securing the spring to the discs, a conducting member of resilient material supported by the eyelet beneath the disc and having a contact portion passing through the notch and overlying the flange.

15 4. A candle light comprising, in combination, a casing having an open end, a lamp conducting means in series with the lamp extending to the open end of the casing, a cup-shaped closure for said open end having an opening in the lower end and capable of relative axial movement with respect to the casing, a base for the casing, a flange surrounding the opening in the closure, a fibre disc carried on the flange inwardly thereof, a metallic disc carried above the fibre disc and spaced from the closure but adapted to engage the conducting means upon relative movement of the closure with respect thereto, a battery positioning spring, metallic means securing the spring to the discs, a conducting member of resilient material supported by the metallic means beneath the disc and formed with a portion normally disposed below the base and having a contact portion passing through the notch and overlying the flange.

20 5. A candle light comprising, in combination, a conductive casing having an open end, a lamp in series with the casing, a cup-shaped closure for the open end having an opening in the lower end, a base for the casing, a flange surrounding the opening in the closure, a fibre disc carried on the flange inwardly thereof and having a notch

25 in its periphery, a metallic disc carried above the fibre disc and spaced from the closure, a battery positioning spring, conductive means securing the spring to the discs, a conducting member of resilient material supported by the conducting means beneath the disc and having a contact portion passing through the notch and overlying the flange and means to move the closure axially to bring the metallic disc in contact with the casing.

30 6. In a candle light, a casing having a conductive end, an end closure therefor having a conductive portion in electrical connection with said conductive end, means permitting said end closure to be advanceable upon the casing, an inwardly compressible contact making member carried with the end closure and comprising a conductive portion in circuit with the battery of the candle light and so disposed as to make contact with the end of the casing to close the circuit when the end closure is advanced upon the casing and a resilient portion normally disposed to make contact with the conductive portion of the end closure to close the circuit when said resilient portion is unrestrained and so proportioned that, when depressed, it is positioned out of contact with said conductive end and the conductive portion of the end closure.

35 7. In a candle light, a casing having a conductive end, an end closure therefor having a conductive portion in electrical connection with said conductive end, means permitting said end closure to be advanceable upon the casing, a movable contact making member comprising a conductive portion in circuit with the battery of the candle light and so disposed as to make contact with the end of the casing to close the circuit when the end closure is advanced upon the casing and a portion to make contact with the conductive portion of the end closure to close the circuit when said member is free to move, yielding means tending to urge the contact making member outwardly and said last named portion being so proportioned that when depressed it is positioned out of contact with said conductive end and the conductive portion of the end closure.
